IGNITRON, SEAL, AND METHOD OF MAKING

Donald E. Marshall, Allwood, N. J., assignor to
Westinghouse Electric Corporation, East Pitts-
burgh, Pa., a corporation of Pennsylvania

Application November 2, 1943, Serial No. 538,700

13 Claims. (Cl. 250—27.5)

1

This invention relates to seals and methods of making the same, and more particularly to such for making a connection through the envelope of mercury-pool cathode devices for connection with the "make-alive" electrodes thereof.

The primary object of my invention, generally considered, is to provide an improved seal through the envelope of an ignitron for connection with the igniter thereof.

Another object of my invention is to provide an improved inlet lead for an ignitron which is adequately insulated from the mercury.

A further object of my invention is to avoid the necessity of cooling the insulation, which was formerly glass, through the lead to the igniter of a mercury-pool cathode device.

A still further object of my invention is to provide a seal for ignitrons involving a combination of "Kovar," ceramic and glass, whereby a stronger and better construction is produced.

An additional object of my invention is the production of a seal for ignitrons involving a ceramic or porcelain capable of withstanding thermal shock and matching the sealing glass in expansion characteristics, as well as the metal parts to which it is connected, whereby a construction mechanically strong and capable of withstanding a temperature of the order of 600° C. to 700° C. is obtained.

Other objects and advantages of the invention, relating to the particular arrangement and construction of the various parts, will become apparent as the description proceeds.

Referring to the drawings illustrating an embodiment of my invention approximately to scale and full size in the original drawings:

Fig. 1 is a vertical sectional view through an ignitron embodying my invention.

Fig. 2 is an exploded view of parts forming the seal for the "make-alive" electrode or igniter.

Fig. 3 is an elevational view of the assembled seal.

Fig. 4 is an axial sectional view of a modified seal, with the lead-in conductor structure including a terminal member in elevation.

The problem of making a connection through the vacuum envelope of a sealed ignitron to the "make-alive" electrode or igniter thereof has never been solved to entire satisfaction. It has been decided best to bring the lead-in conductor through the cathode header and the mercury pool. Thus it is necessary that the seal be vacuum-tight and that the inlet head be adequately insulated from the mercury. It has been the practice to use glass in all such cases. It has

2

been recently discovered that the energy liberated by the igniter arc is capable of heating such glass to temperatures well in excess of 600° C. For this reason it has been necessary to cool the glass forming the seal by conduction through the metallic lead. Thus the glass insulation has had to be intimately sealed to the lead-in conductor, which is thus necessarily made of such material as "Kovar" or tungsten. This has resulted in constructions which are not strong and, therefore, subject to considerable breakage in manufacturing and subsequent handling.

In accordance with my invention, I form a good seal by using a combination of "Kovar" or other suitable seal metal, ceramic, and glass having a coefficient of expansion matching that of the metal and the ceramic, with or without steel. Two embodiments of my invention are illustrated in the drawings, the first one representing the use 10 of a "Kovar" cap with a steel center lead, the alternative design representing the use of a "Kovar" rod sealed directly to a glass coating on a ceramic cylinder. I prefer the first design as requiring less exact expansion-matching of the 15 various component materials, due to the greater possibility of flexure of the "Kovar" cap, as compared with the "Kovar" rod.

I have found that the choice of the proper ceramic body is important. It must match 20 "Kovar" sealing glass in expansion and be capable of withstanding a considerable amount of thermal shock. It must be mechanically strong and capable of withstanding temperatures of the order of 600° to 700° C. After trying a number 25 of materials, I have found that the best are that designated as Stupakoff body #655, as manufactured by Stupakoff Laboratories, Inc., Latrobe, Pa., and that called E-35 by its manufacturer, Westinghouse Electric Corporation, East Pitts- 30 burgh, Pa.

Referring now to the drawings in detail, like parts being designated by like reference characters, and first considering the embodiment of my invention illustrated in Figs. 1, 2 and 3, there is 35 shown a rectifier 10 of the type called an ignitron, comprising a metal envelope or housing 11 enclosing a mercury cathode 12, and a solid anode 13 insulated therefrom. The floor or bottom wall 14 of the ignitron has a power lead 20 and an opening 15 through which the lead-in conductor 16 to the "make-alive" electrode or igniter 17 extends.

In accordance with the present embodiment of 40 my invention, I seal a preferably steel lead 16 through the opening 15 of the ignitron housing,

by taking a hollow ceramic cylinder 18, which the lead-in conductor 16 loosely fits, and coating or beading the normally-lower end portion thereof with glass 19. The glass 19 (which may be Corning #704) is of such a composition that it satisfactorily seals with, not only to the ceramic or porcelain cylinder 18, but also the connecting metal part or parts, preferably formed of "Kovar" which, as is well known, is a patented alloy having the following composition: 28.7% to 29.2% Ni, 17.3% to 17.8% Co, 52.9% to 53.4% Fe, not more than .06% C, not more than .5% Mn and not more than .2% Si.

I next take an eyelet 21, of "Kovar" or other metal which seals satisfactorily to the glass used, comprising a hollow cylindrical portion 22 and an outstanding annular flange 23 at its normally-upper end, and embeddingly seal the free edge of said cylindrical portion 22 into the normally-upper end portion of the glass coating 19, to produce the seal illustrated in Fig. 1.

The lead-in conductor structure is completed by providing the lead portion 16 at its normally lower end, with a head or circular flange portion 24 and I weld, braze, or otherwise securely electrically connect the lower or outer surface of this head to the inner surface of a cup 25, of "Kovar" or other metal which seals satisfactorily to the glass used.

To the outer surface of the bottom wall 23 of the cup 25, I weld, braze, or otherwise securely electrically connect a short pin 27, which pin desirably corresponds in material and diameter with that of the lead-in conductor 16. To this pin I similarly secure an outer terminal contact member 28, which may be formed of any desired conductive material, such as brass.

The assembled lead-in conductor, cup, pin and terminal contact member is then connected to the assembled glass coated ceramic 18 and eyelet 21, by inserting the upper or free end of the lead-in conductor 16 through the ceramic cylinder and embeddingly sealing the free edge of the cup 25 into the glass coating 19, to produce the lead-in assembly illustrated in Fig. 1. The upper portions of the assembly are then inserted in the aperture 15, as illustrated, and the flange 23 of the eyelet 21 welded, or otherwise suitably connected, to the bottom wall 14. The igniter 17, which may be of conventional form, is then secured to the upper portion of the lead-in conductor 16 to produce the complete assembly illustrated in Fig. 1.

Referring now to the embodiment of my invention illustrated in Fig. 4, there is shown a construction somewhat similar to that of Figs. 1 to 3, inclusive, in that the ceramic or porcelain cylinder 18^a receives lead-in conductor 16^a and has at its lower end a terminal member 28^a, said lead-in conductor being sealed to the ceramic 18^a, as well as the "Kovar" eyelet 21^a, by means of a glass coating 19^a.

However, in the present embodiment the glass coating is formed as a relatively large bead in which the ends of both the cylinder 18^a and eyelet 21^a are embedded. The lead-in conductor 16^a is necessarily formed of "Kovar," or some other material matching the glass 19^a, as the seal with said glass is relied upon in making a vacuum-tight assembly. This makes it undesirable to make the lead-in conductor 16^a of steel, as was done in the preceding embodiment. As in said preceding embodiment, however, the "Kovar" eyelet 21^a may be similarly formed with a flange 23^a for connection with the lower wall of an ignitor envelope.

From the foregoing disclosure, it will be seen that I have provided improved seals particularly adapted for use with ignitrons, but not necessarily limited to such use, glass being replaced by a ceramic or porcelain which can successfully withstand relatively high temperatures occurring in service, thereby avoiding the necessity for cooling such through the lead, and at the same time producing a much stronger construction.

Although preferred embodiments of my invention have been disclosed, it will be understood that modifications may be made within the spirit and scope of the appended claims.

I claim:

1. A seal comprising a hollow ceramic cylinder with a glass coating fused on a portion of its exterior, a metal eyelet through which said cylinder passes and projects beyond both ends, embedded in one end of said coating, and having an outstanding flange for connection to the wall of a vessel, and a lead-in conductor passing through said cylinder and sealed thereto by means of said coating.

2. A seal comprising a hollow ceramic cylinder with a glass coating fused on a portion of its exterior, a metal eyelet through which said cylinder passes, embedded into one end of said coating, and having an outstanding flange for connection to the wall of a vessel through which said cylinder passes, a lead-in conductor passing through said cylinder, and a metal cap to the inner surface of which the outer end of said lead-in conductor is secured, said cap having its edge fused into the adjacent end of said glass coating to complete the connection to said cylinder.

3. A seal comprising a hollow ceramic cylinder with a glass coating fused on a portion of its exterior, a metal eyelet through which said cylinder passes, embedded into one end of said coating, and having an outstanding flange for connection to the wall of a vessel through which said cylinder passes, and a lead-in conductor passing through said cylinder and said glass coating, the coating sealing said cylinder, eyelet and lead-in conductor adjacent one end of the cylinder.

4. A seal comprising a hollow B-35 ceramic cylinder with a glass coating, of coefficient of expansion corresponding thereto and to "Kovar," fused on a portion of its exterior, a "Kovar" eyelet through which said cylinder passes, embedded into one end of said coating, and having an outstanding flange for connection to the wall of a vessel through which said cylinder passes, and a lead-in conductor structure having one portion passing through said cylinder and another portion sealed thereto by means of said coating.

5. A seal comprising a hollow B-35 ceramic cylinder with a glass coating, of coefficient of expansion corresponding thereto and to "Kovar," fused on a portion of its exterior, a "Kovar" eyelet through which said cylinder passes, embedded into one end of said coating, and having an outstanding flange for connection to the wall of a vessel through which said cylinder passes, a steel lead-in conductor passing through said cylinder, and a "Kovar" cap to the inner surface of which the outer end of said lead-in conductor is secured, said cap having its edge fused into the adjacent end of said glass coating to complete the connection to said cylinder.

6. A seal comprising a hollow B-35 ceramic cylinder with a glass coating, of coefficient of expansion corresponding thereto and to "Kovar," fused on a portion of its exterior, a metal eye-

let through which said cylinder passes, embedded into one end of said coating, and having an outstanding flange for connection to the wall of a vessel through which said cylinder passes, and a "Kovar" lead-in conductor passing through said cylinder and said glass coating, the coating sealing said cylinder, eyelet and lead-in conductor adjacent one end of the cylinder.

7. An ignitron comprising a metal envelope, an anode suspended in and insulated from said envelope, a pool of mercury resting on the bottom wall of said envelope to function as a cathode, a power lead extending from said bottom wall, an igniter electrode dipping into said mercury, a lead structure connected to said igniter electrode and insulated from said bottom wall by means of a seal comprising a hollow ceramic cylinder with a glass coating fused on a portion of its exterior, and a metal eyelet through which said cylinder passes, embedded in one end of said coating, and having an outstanding flange connected in vacuum-tight relationship with said envelope bottom wall, said last-mentioned lead structure having one portion passing through said bottom wall and cylinder, and another portion sealed to the latter by means of said coating.

8. An ignitron comprising a metal envelope, an electrode adapted to act as an anode suspended in and insulated from said envelope, a pool of mercury adapted to function as a cathode resting on the bottom wall of said envelope, a power lead extending from said bottom wall, an igniter electrode dipping into said mercury, and a lead to said igniter electrode insulated from said bottom wall by means of a seal comprising a hollow ceramic cylinder with a glass coating fused on a portion of its exterior, a metal eyelet through which said cylinder passes, embedded into one end of said coating, and having an outstanding flange connected in vacuum-tight relationship with said envelope bottom wall, said last-mentioned lead passing through said bottom wall and cylinder, and a metal cap to the inner surface of which the outer end of said lead-in conductor is secured, said cap having its edge fused into the adjacent end of said glass coating to complete the connection to said cylinder.

9. An ignitron comprising a metal envelope, an electrode adapted to function as an anode suspended in and insulated from said envelope, a pool of mercury resting on the bottom wall of said envelope and adapted to function as a cathode, a power lead extending from said bottom wall, an igniter electrode dipping into said mercury, and a lead structure connected to said igniter electrode and insulated from said bottom wall by means of a seal comprising a hollow ceramic cylinder with a glass coating fused on a portion of its exterior, and a metal eyelet through which said cylinder passes, embedded into one end of said coating, and having an outstanding flange connected in vacuum-tight relationship with the envelope bottom wall, said last-mentioned lead structure having one portion passing through said cylinder and glass coating, the coating sealing said cylinder, eyelet and another portion of said lead structure adjacent one end of the cylinder.

10. The method of making a seal, comprising

coating the exterior of one end portion of a hollow ceramic cylinder with glass, placing a metal eyelet over the other end of said cylinder and fusing the adjacent edge portion into said glass coating, passing one portion of a lead-in conductor through said cylinder, and sealing another portion of said structure thereto by means of the other end portion of said coating.

11. The method of making a seal comprising coating the exterior of one end portion of a hollow ceramic cylinder with glass, placing a metal eyelet over the other end of said cylinder and fusing the adjacent edge portion into said glass coating, sealing a metal cap to one end portion of a lead-in conductor, passing the other end portion of said conductor through said cylinder, and sealing the edge of said cap into the adjacent end of said glass coating to complete the connection to said cylinder.
12. The method of making a seal comprising coating the exterior of one end portion of a hollow ceramic cylinder with glass, embedding one end of a metal eyelet through which said cylinder passes into the end of said coating adjacent the uncoated portion of said cylinder, and passing a lead-in conductor through said cylinder and glass coating so that the latter effects a seal between the conductor, eyelet, and cylinder.
13. An ignitron comprising a metal envelope, an electrode adapted to function as an anode suspended in and insulated from said envelope, a pool of mercury supported by the bottom wall of said envelope to function as a cathode, a power lead extending from said bottom wall, an igniter electrode dipping into said mercury, and a lead structure for said igniter electrode insulated from said bottom wall by means of a seal comprising a hollow ceramic cylinder extending from below said bottom wall to above said mercury, with a relatively-thick glass coating fused on a portion only of its exterior near its lower end, a metal eyelet through which said cylinder loosely passes, the lower end of said eyelet being embeddedly sealed into the upper end portion of said coating and having an outstanding flange connected in vacuum-tight relation with the envelope bottom wall, said lead structure having one portion passing through said cylinder and the lower portion of the glass coating thereon embeddedly sealing another portion of said lead to said cylinder adjacent the lower end of the latter.
